Primary Examiner — Elizabeth Albert(74) *Attorney, Agent, or Firm* — Kagan Binder, PLLC(57) **CLAIM**

The ornamental design for a plant pot, as shown and described.

DESCRIPTION

FIG. 1 is a perspective view of a plant pot showing our new design;

FIG. 2 is a front elevation view thereof;

FIG. 3 is a right side view thereof;

FIG. 4 is a top plan view thereof;

FIG. 5 is a bottom plan view thereof; and,

FIG. 6 is another perspective view thereof.

The broken lines are included for the purpose of showing portions of the plant pot that form no part of the claimed design.
